UNITED STATES PATENT OFFICE.

ELIJAH S. GRAMMER, OF KANASKAT, WASHINGTON.

SNATCH-BLOCK.

SPECIFICATION forming part of Letters Patent No. 737,222, dated August 25, 1903.

Application filed February 24, 1903. Serial No. 144,745. (No model.)

To all whom it may concern:

Be it known that I, ELIJAH S. GRAMMER, a citizen of the United States, residing at Kanaskat, in the county of King and State of Washington, have invented certain new and useful Improvements in Snatch-Blocks, of which the following is a specification.

My invention relates to certain new and useful improvements in snatch-blocks.

10 The object of my invention is to provide a snatch-block that may be readily opened to allow the bite of a cable or rope drawn taut over the pulley or sheave to go free.

My snatch-block is more especially designed 15 for use in logging-camps, where steam winding-gear using a steel cable and strong snatch-blocks are required. In such instances an opening snatch-block adapted to quickly release the bite of the cable is essential. Such 20 a block I have designed, which may be quickly opened by simply removing the pin and allowing the sheave-shell to swing downwardly, thus immediately releasing the cable.

Finally, the object of my invention is to 25 provide a device of the character described that will be strong, durable, efficient and simple, and comparatively easy to manufacture.

In the accompanying drawings, forming a 30 part of this specification, and in which like numerals of reference indicate corresponding parts throughout the several views, Figure 1 is a side elevation of my improved snatch-block. Fig. 2 is a side elevation of the same 35 partly "open" and showing the cross-head in section. Fig. 3 is a top plan view of Fig. 1, and Fig. 4 is a bottom view of the cross-head and strap forming a part of my invention.

Reference-numeral 1 designates a sheave 40 or pulley of the ordinary construction rotatably mounted upon a shaft 2, secured in a shell or frame 3, which comprises two substantially circular cheek-plates 4 4', connected at their rear ends by the portion 4". To 45 the upper cheek-plate 4 is attached a strap 6, extending beyond its forward edge, and to the lower plate 4' is also attached a strap 8, shorter than the upper strap and which does not extend to the front edge of the lower 50 plate. These straps are formed from strip metal or other like material, which is bent upon itself to form a cylindrical portion,

which is provided with a cut-out portion 7', thereby forming two cylindrical projections or locking members 7 7'. The ends of these 55 straps are carried back and are secured by rivets 5 to the cheek-plates and, further, are provided with apertures 2', through which the ends of the shaft 2 project. The latter member 8 is hinged to a right-angular cross-head 9 of corresponding width by means of a pin 11, passing through the projections 7 7' and through a substantially cylindrical lug or projection 10, formed on the horizontal portion of the cross-head. The upper end of the cross-head 60 is also provided with a lug or locking portion 10', similar to that, 10, at the other end. A removable locking-pin 11' passes through the cylindrical projections 7 7' on the upper strap and through the said lug 10' to lock the 70 shell or frame 3, with the cross-head, in an operative position. It will be observed that the ends of the straps are alike, as are also the ends of the cross-head. This is done in order that the pins 11 11' may be alike and 75 interchangeable, thus materially reducing the expense in manufacture. Further, it will be noticed that the forward end of the lower plate 4' when the device is in its locked position, as shown in Fig. 1, rests 80 upon the upper face of the cross-head to form a stop and to reduce the vibration incident to devices of this character. A swivel 14 is journaled in the vertical part of the cross-head and held therein by the head or "up-set" part 15. A link connects the said swivel 85 with a hook 16 of any desired construction.

The operation of my device is as follows: Assuming that the hook 16 has been attached to some article and it is desired to pass a 90 rope around the pulley, the pin 11' is withdrawn. Thereupon the device opens by reason of the greater weight of the rear portion hinging upon the pin 11, as illustrated in Fig. 2. The cable or rope is then thrown over 95 the forward end of the strap 6 to engage the pulley or sheave and the device relocked in an operative position, as seen in Fig. 1.

It will be evident that in case of necessity the pin 11 may be removed, causing the device to 100 hinge on pin 11', or both pins may be removed, thus separating the cross-head from the frame and pulley; but this is not the usual practice.

I do not wish to confine my invention to the exact details above enumerated and described, as I may make various changes and alterations wholly within the scope of my claims and without departing from the spirit of my invention.

Having fully described my invention, what I claim as new and useful, and desire to secure by Letters Patent, is—

- 10 1. In a snatch-block, the combination of a sheave-shell, a sheave, a shaft passing through said sheave-shell and sheave, a right-angular cross-head, lugs provided on the ends of said cross-head, straps doubled upon themselves to form cylindrical locking members, said straps secured to said sheave-shell and receiving the ends of said shaft, and pins passing through said cylindrical locking mem-
- 15

bers and through said lugs, substantially as and for the purpose set forth.

2. In combination with the angular cross-head, an approximately U-shaped shell, a sheave journaled in said shell, a short strip secured to one side of said shell and having one of its ends pivoted to one end of said cross-head, an elongated strip secured to the opposite side of the said shell, means for securing said last-named strip to the said cross-head and a swivel secured to said cross-head intermediate said strips.

In testimony whereof I affix my signature in presence of two witnesses.

ELIJAH S. GRAMMER.
